UNITED STATES PATENT OFFICE.

WILLIAM MARTIN ELLIOTT, OF AUSTIN, TEXAS.

ELECTRIC-LAMP SOCKET.

1,178,479.

Specification of Letters Patent.

Patented Apr. 4, 1916.

Application filed April 27, 1915. Serial No. 24,273.

To all whom it may concern:

Be it known that I, WILLIAM M. ELLIOTT, a citizen of the United States, residing at Austin, in the county of Travis and State of Texas, have invented a new and useful Electric-Lamp Socket, of which the following is a specification.

The present invention appertains to electric lamp sockets, and aims to provide a novel and improved incandescent electric lamp socket having a pair of switches which are alternately closed and opened, and having means for the attachment thereto of three conductors, whereby it is possible to light the lamp by means of a main switch notwithstanding the fact that the socket switches might have been previously operated for extinguishing the lamp.

With the use of an ordinary lamp socket in a chandelier or drop light, and connected to a wall or main switch, it is frequently the case that the socket switch is operated for extinguishing the lamp, instead of employing the wall or main switch, and this would open the socket switch, to prevent the lamp from being subsequently lighted by operating the wall or main switch. It would therefore be necessary for the person to find the socket and close the switch thereof before the wall or main switch could be operated for controlling the light. The disadvantages incident to this arrangement will be readily appreciated, and are well known.

The present invention provides means for remedying the said objectionable conditions, by the provision of a pair of switches carried by the socket, and connected by the three wires or conductors to the main or wall switch, whereby the lamp may always be lighted by either the main switch, or the socket switches; whichever is desired.

The cardinal feature of the invention resides in the provision in a lamp socket, of unique means for the attachment of three conductors to the socket, and whereby the conductors may be connected properly within the socket for the desired purposes.

It is also within the scope of the invention to provide a lamp socket having the features above noted and which will not be appreciably more expensive or complicated than the ordinary lamp socket, the improved features being comparatively simple, and being readily incorporated in present day lamp sockets.

With the foregoing and other objects in

view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a diagrammatical view of the socket and circuits. Fig. 2 is a longitudinal section of the socket. Fig. 3 is a cross section of the socket taken on the line 3-3 of Fig. 2.

In carrying out the invention, the lamp socket comprises, as usual, a shell 1 having a cap 2, and containing the upper and lower insulating members or blocks 3 and 4, respectively, a socket member or shell 5 being secured to the lower insulating member 4 and being adapted to receive the plug 6 of the electric lamp 7. A binding post 8 is secured between the insulating members 3 and 4 and is connected by means of a screw or other element 9 to the socket member 5. A screw or bolt 10 is engaged centrally through the lower insulating member 4, and a V-shaped spring contact 11 is secured to the lower end of the screw 10 for engaging the central contact terminal of the lamp 7 in the usual manner. Attached to the upper end of the screw 10 is an upwardly curved leaf spring 12 providing a switch or contact member. A transverse spindle 13 is journaled between the insulating members 3 and 4, diametrically of the socket, and is provided at its outer end with a finger piece 14. The spindle 13 carries a cam 15 within the chamber between the insulating members, and a curved leaf spring 16 is secured between the insulating members remote from the free end of the spring switch 12. The free end of the leaf spring or spring switch 16 overhangs the spring switch 12 and is provided with a downturned lip or portion 17 to contact with or bear upon the spring switch 12 when the spring switch 16 is pressed downwardly by the cam 15.

A binding post member 18 is secured between the insulating members and is provided with a downturned contact finger 19 overhanging the free end of the spring switch 12 and against which the free end of

the spring switch 12 is adapted to bear when the spring switch 16 releases the spring switch 12. The parts are properly insulated from one another as will be apparent to those skilled in the art, to prevent short circuiting.

Three conductors which are passed through the cap 2 are connected to the spring switches and binding post 8 of the lamp socket. Thus, one conductor 20 is connected to the binding post 8, another conductor 21 is connected to the butt or basal end of the spring switch 16, and the third conductor 22 is connected to the binding post member 18. The conductor 20 has the generator or source of electrical energy 23 interposed therein, and is connected to the main or wall switch 24 which co-operates with a pair of contacts 25 and 26 to which the respective conductors 21 and 22 are connected.

In operation, supposing the spindle 13 is swung so that the cam 15 allows the spring switch 16 to spring away from the spring switch 12, the free end of the spring switch 12 will engage the contact finger 19 and this will limit the movement of the spring switch 12, so that the two spring switches 12 and 16 are separated or spaced apart. Then, by operating the main or wall switch 24 to engage the contact 26, the circuit through the lamp 7 will be closed, the current flowing from the generator 23 through the conductor 20, binding post 8, screw 9, socket member 5, lamp 7, spring contact 11, screw 10, spring switch 12, binding post member 18, conductor 22, switch 24 and back to the generator. When the switch 24 is swung away from the contact 26 into engagement with the contact 25, the circuit will be broken or opened, to extinguish the lamp. Supposing, however, that the switch 24 is left in engagement with the contact 26, and the spindle 13 of the lamp socket is turned to cause the cam 15 to force the spring switch 16 downwardly, so as to engage the spring switch 12, and which will move the spring switch 12 downwardly out of engagement with the contact finger 19, to thereby open the circuit through the lamp 50 for extinguishing the same, the lamp may be lighted subsequently by operating the main switch 24. By swinging the main switch 24 into engagement with the contact 25, the current from the generator 23 will flow through the conductor 20, binding post 8, screw 9, socket member 5, lamp 7, spring contact 11, screw 10, switch member 12, switch member 16, conductor 21 and switch 24 back to the generator. By swinging the switch 24 away from the contact 25, the circuit will be

opened. When the switch 24 engages either one of its contacts, a circuit through the lamp may be closed and opened by operating the spindle 13, so that it will be evident that the circuit through the lamp may be controlled by either the main or wall switch, or the socket switches. The switches of the lamp socket are alternately closed and opened, it being noted that the spring switch 12 not only serves its function as a switch, but also serves as a spring contact for the engagement of the spring switch 16.

The main or wall switch 24 may be ordinary construction, the same only being illustrated diagrammatically in the drawing, and it will also be understood that the wiring may be arranged properly under the various conditions, to the ends above noted.

From the foregoing, taken in connection with the drawing, it is believed that the advantages and capabilities of the present invention will be obvious to those versed in the art, without further comment being necessary.

The binding post member is preferably secured to the upper insulating member 3, although it may be secured in any suitable manner to an appropriate part of the socket.

A number of the present lamp sockets may be connected in multiple with the main switch 24, whereby the main switch provides a master switch for controlling all of the lamp sockets, and whereby all of the lamps may be extinguished by the main or master switch.

Having thus described the invention, what is claimed as new is:

1. In a circuit controller, a contact, a spring switch engageable therewith, a second spring switch engageable with the first mentioned spring switch, and means for operating the second spring switch to engage and move the first mentioned spring switch away from the contact.

2. In a lamp socket, a contact, a spring switch the free end of which is adapted to bear against the contact, a second spring switch having its free end overhanging the first mentioned spring switch to engage the same, and means for operating the second spring switch to engage and move the first mentioned spring switch away from said contact.

In testimony that I claim the foregoing as my own, I have hereto affixed my signature in the presence of two witnesses.

WILLIAM MARTIN ELLIOTT.
